UNITED STATES PATENT OFFICE

147,260

DESIGN FOR A SCORING TEE

Dorin A. David, Bakersfield, Calif.

Application April 22, 1946, Serial No. 128,838

Term of patent 3½ years

(Cl. D34—5)

To all whom it may concern:

Be it known that I, Dorin A. David, a citizen of the United States, residing at Bakersfield, county of Kern, and State of California, have invented a new, original, and ornamental Design for a Scoring Tee, of which the following is a specification, reference being had to the accompanying drawing, forming part thereof.

Fig. 2 is a side elevational view thereof.

Fig. 3 is a three-quarter perspective view thereof.

I claim:

The ornamental design for a scoring tee, substantially as shown.

DORIN A. DAVID.
